STEP-BY-STEP FEEDING MECHANISM

John Wallerius, Glen Ellyn, and Harry E. Locey,
Oak Park, Ill., assignors to Sunbeam Corpora-
tion, Chicago, Ill., a corporation of Illinois

Application August 24, 1949, Serial No. 112,062

1 Claim. (Cl. 214—18)

1 This invention relates to feed mechanisms for furnaces and more particularly to feed mechanisms in which there is both a horizontal and a vertical movement and the movements are so coordinated that an article can be advanced through a furnace in a step by step manner.

Heretofore feed mechanisms of the above character have not been satisfactory in all respects. For example one of the objections to prior feed mechanisms of this character is that they are rather complicated. Too, they have also employed cams for effecting the respective movements and because of the stresses involved the cams wear. As a result uniform horizontal and vertical movements are not obtained and consequently the articles are not fed through the furnace properly. Another objection has been that the cams have to be replaced frequently. Due to the complex character of feeding mechanisms for prior designs of furnaces the feed mechanisms are rather difficult to service and consequently the maintenance costs are relatively high.

Accordingly, an object of this invention is to provide a novel feed mechanism of the above character with means for effecting a positive movement in both horizontal and vertical directions.

Another object of the invention is to provide a feed mechanism of the above character that is simple to construct, that permits accessibility to all moving parts, that is easy to service, and that is relatively inexpensive to produce.

Other objects and advantages of the invention will become apparent from the following detailed description taken in connection with the accompanying drawings, in which—

Figure 1 is a longitudinal sectional view of a furnace embodying the present invention with the vertically movable support means in a raised position;

Fig. 2 is a fragmentary view similar to Figure 1 showing the vertically movable support means in a retracted position;

Fig. 3 is an end view of Figure 1; and

Fig. 4 is an enlarged sectional view taken substantially along the lines 4—4 of Figure 1.

Referring now to the drawings, the invention is shown embodied in a feed mechanism for a furnace designated generally by the numeral 11. In general the furnace includes a bottom portion 12, sides 13 and 14 and a top (not shown) formed of suitable refractory material, and defining a heating chamber 16 having openings 17 and 18, respectively, at the charge and discharge end of

the furnace 11. The furnace may be heated by any suitable means. For purposes of simplifying the drawings, the latter has been omitted. Vertically movable doors 21 and 22, respectively, close the openings 17 and 18. The feed mechanism in general comprises carrier means reciprocable between horizontal positions for moving workpieces 19 horizontally between preselected positions and vertically movable support means for supporting the workpieces and movable between a retracted position in which the workpieces rest on the horizontally movable carrier for movement in unison therewith and a position in which the workpieces 19 are raised above the carrier to permit the carrier to be moved horizontally independently of the workpieces 19. Suitable means may be utilized for coordinating the respective movements of the carrier and the support means so that the workpieces are advanced in a step by step manner through the heating chamber 16 of the furnace 11.

As best seen in Figs. 1 and 4 the carrier means comprises a pair of link chains 23. The latter are disposed in spaced trough shaped guideways 26 disposed lengthwise on the bottom 12 of the furnace 11. Preferably the guideways are formed of material having good wear resisting qualities, one such material being Carborundum. At the charge end of the furnace the chains 23 are supported by spaced sprockets 27 mounted on a transversely extending shaft 28. The latter is supported by a suitable support 29 mounted on the framework 31 supporting the furnace 11. The shaft 28 is spaced from the charge end of the furnace a sufficient distance so that the portions of the chains 23 between the sprockets 27 and the end of the furnace 11 form a table portion at the charge end of the furnace for supporting the workpieces. After passing over the sprockets 27 the chains 23 are connected to a crosshead 33. The crosshead is connected to one end of a piston (not shown) of a pressure fluid unit 34 by a rod 36. The pressure fluid unit 34 is shown mounted on the framework 31 beneath the bottom 12 of the furnace 11. At the opposite end of the furnace the chains 23 are mounted on spaced sprockets 37 (one only being shown) mounted on a transversely extending shaft 38, the latter being supported by a suitable support 39 mounted on the framework 31. The shaft 38 is spaced from the discharge end of the furnace a sufficient distance so that the portions of the chains 23 between the sprockets 37 and the end of the furnace form a table portion for supporting the workpieces after they are discharged from the

furnace. After passing over the sprockets 37 the ends of the chains 23 are interconnected by a crosshead 41 which in turn is connected to the opposite end of the piston in the pressure fluid unit 34 by a cable 42. A turnbuckle 43 is connected in series with the cable 42 for varying the slack in the chains 23 to permit of adjustment of the tension in the chains 23.

The flow of pressure fluid to the pressure fluid unit 34 is under the control of a suitable conventional control valve unit 44. The latter is connected with opposite ends of the pressure fluid unit 34 by conduits 46 and 47, respectively, and is connected to a pressure fluid source by a conduit 48. Inasmuch as any conventional valve unit 44 may be utilized, for purposes of simplifying the drawings in this instance, the valve unit 44 is shown herein by symbol only. With this construction the flow of pressure fluid may be directed to either end of the pressure fluid unit 34. Thus, by alternately applying the pressure fluid first to one end of the unit 34 and then to the other end the chains 23 may be caused to reciprocate between opposed positions, the distance of movement being equal to the stroke of the piston in the unit 34.

The vertically movable support means, in this instance, includes a plurality of vertically disposed uprights 51 extending through openings 52 in the bottom 12 of the furnace. The uprights 51 are disposed in aligned rows adjacent the side walls 13 and 14, respectively, of the furnace. Spaced outwardly from opposite ends of the furnace are spaced uprights 53, respectively, in alignment with the rows of uprights 51. Beams 54 extending between adjacent uprights in each row are suitably supported to have their upper surfaces disposed in a substantially common plane and to define spaced workpiece supports extending lengthwise of the furnace shaped to support opposite edges respectively of workpieces 19 being advanced through the furnace. To support the beams the uprights 53 are formed with caps 56 including a central portion 57 extending upwardly from spaced shoulders 59 and the uprights 51 are provided with caps 58 including a central portion 65 extending upwardly from spaced shoulders 60. The tops of the central portions 57 and the tops of the central portions 65 are disposed in a substantially common plane. As best seen in Figs. 3 and 4 the beams 54 have an inverted U-shaped cross section and are arranged so that the bridging portion of the beams rests on the tops of the central portions and the leg portions straddle the central portions. Each of the beams 54 is pivotally mounted at one end and has its opposite end freely supported. Adjacent beams 54 are in spaced endwise relation to allow for expansion of the beams when the furnace is brought up to temperature. The uprights 51 are mounted for reciprocation in suitable vertically arranged guides 61 attached to and depending from the bottom 12 of the furnace and the uprights 53 are supported in suitable guides 62 supported on the framework 31 at opposite ends of the furnace.

At the bottom of each upright is a toggle joint 70. The toggle joints for the uprights 51 and 53 are of similar construction. For purposes of simplification therefore only one of the toggle joints 70 will be described in detail. As best seen in Fig. 4 each toggle joint 70 includes spaced bars 66 each pivotally connected at one end to a pin 67. The latter extends through the upright 51 and projects through vertically elongated slots 68 formed in the guide 61 on opposite sides of

the upright 51. The opposite ends of the spaced bars 66 are respectively pivotally connected to one end of spaced bars 69 as by a pin 71. The opposite ends of the spaced bars 69 are pivotally supported on a shaft 72. The latter is supported by suitable spaced supports 73 mounted on spaced channel irons 74 forming a part of the framework 31. The supports 73 are disposed in spaced axial relation to the lower ends of the respective uprights. A spacer 76 maintains the lower ends of the bars 69 in spaced relation. The pivotal connection between the spaced bars 66 and 69 forms a knee.

Driving links 77 extend lengthwise of the framework 31 below the furnace 11 in alignment with each row of uprights. Each link 77 is pivotally connected to all of the knees in one of the rows of uprights. As best seen in Fig. 4 the driving links 77 are supported on pivot pins 78 between the spaced bars 69. Spacers 79 position the link 77 intermediate the bars 69.

Suitable provision is made for moving the links 77 to simultaneously move all of the knees of the toggle joints 70 between opposed positions on one side of an axis defined by alignment of the bars 66 and 69 to raise the uprights to a position in which the top surfaces of the beams 54 are above the workpiece supporting surfaces of the chains 23 and a retracted position in which the top surfaces of the beams 54 are below the supporting surfaces of the chains 23. As shown in Figs. 2 and 3, at the charge end of the furnace, each driving link 77 is connected to a link 79 in turn pivotally connected to one end of an arm 81; the latter is keyed to a shaft 82 supported by suitable bearings, not shown, mounted on vertical members 83 forming part of the framework 31. Intermediate the arms 81 is an arm 84 keyed to the shaft 82 and having its free end pivotally connected to one end of a piston (not shown) mounted in a pressure fluid unit 87. The pressure fluid unit in this embodiment of the invention is under the control of a control valve unit 88. The latter is connected to opposite ends of the pressure fluid unit by conduits 89 and 91, respectively, and to a source of pressure fluid by a conduit 82.

The control valve units 44 and 88 may be provided with a suitable timing mechanism incorporated in each unit in a conventional manner to coordinate the movements of the carrier and the support means. The opening and closing of the doors 21 may also be controlled by the timing mechanisms in the control units so that the doors open and close in coordinated timed relation with the horizontal movement of the carrier and the vertical movement of the supports. Where desired a master timing device may be employed for controlling the movements of the carrier and supports means and the opening and closing of the doors.

The operation of the foregoing feed mechanism is apparent from the above description but may be summarized briefly as follows: As shown in Figure 1 the vertically movable supports are in their raised position. With the parts in this position the operator places workpieces 19 on the beams 54 at the charge end of the furnace. The uprights 51 and 53 are then moved to a retracted position. This is effected by applying pressure fluid to the pressure fluid unit 87 to cause the arm 84 to rotate in counterclockwise direction as viewed in Figs. 1 and 2. Simultaneously the arm 81 is rotated in a counterclockwise direction and the driving links 77 are shifted to the left of the position they

assume in Figure 1. At the conclusion of this shifting movement the links 77 are in the position shown in Fig. 2 and the uprights are in a retracted position so that workpieces rest on the chains 23. Simultaneously with the retraction of the support means pressure fluid is applied through the conduit 46 to the left hand end (as viewed in Figure 1) of the pressure fluid unit 34 to effect movement of the chains 23 through the furnace. This advances the workpieces 19 in the direction of the furnace a distance corresponding to the length of the stroke of the piston in the pressure fluid unit 34. At the conclusion of this movement of the chains the support means is raised to lift the workpieces 19 above the chains 23. This is effected by applying pressure fluid to the unit 87 to cause the arm 84 to rotate in a clockwise direction as viewed in Fig. 2. Simultaneously the arm 81 is rotated in a clockwise direction and the driving links 77 are shifted from their position shown in Fig. 2 to the position they assume shown in Figure 1. During this movement the knees of the toggle joints are moved to the right. Normally the bars 66 and 69 are disposed at an angle to each other. As the knees are moved to the right from the position they have in Fig. 2 they are urged toward a position of alinement. As they approach alinement the uprights 51 and 53 are forced upwardly. The closer the bars approach alinement the greater the force applied to the uprights. As soon as the workpieces 19 clear the chains 23 pressure fluid is applied to the pressure fluid unit 34 in a direction to effect reverse movement of the chains 23 a distance again corresponding to the length of the stroke of the piston of the unit 34. The support means is then lowered as described above and so that the workpieces again rest on the chains 23. Pressure fluid is again directed to the pressure fluid unit 34 to effect forward movement of the chains 23 to advance the workpieces farther into the furnace. If it is desired to advance the workpieces rapidly through the furnace in a step by step manner the above cycle is repeated the required number of times to move the workpieces the length of the heating chamber 16. In some instances it may be desirable to leave the workpieces 19 in a particular heating zone in the furnace for a certain length of time. This may be accomplished by varying the length of time between operations of the carrier or the vertical support means. This construction has many advantages as are readily apparent to those skilled in the art. It is simple. The operation of the carrier and supports is positive. Moreover the feed mechanism is relatively inexpensive to manufacture.

While we have shown one embodiment of our

invention it will be understood that we do not wish to be limited thereto since many modifications may be made and we therefore contemplate by the claim to cover such modifications as fall within the true spirit and scope of our invention.

We claim:

In a mechanism for feeding an article to a furnace, the combination of spaced link chains extending horizontally through the furnace, sprockets at opposite ends of the furnace for supporting the chain, pressure fluid means connected to opposite ends of the chains for effecting reciprocable movement of the portion of the chain in the furnace between preselected positions, a plurality of vertically movable uprights disposed in aligned rows, guide means for said uprights, beams extending between adjacent uprights in each row to define a support means having spaced surfaces shaped to engage opposite edges of an article and movable between a retracted position in which the surfaces are below the top of the chains and a raised position in which the surfaces are above the top of the chain, said beams being arranged in end to end relationship with a space between adjacent ends thereof, a first bar pivotally connected to each upright, a second bar pivotally connected to each of said first bars, means for pivotally mounting the opposite end of each of said second bars to be in substantially alined relation with said uprights and to be at one side of the connection between the first and second bars, a driving link for each row of uprights pivotally connected to each first and second bar in each of said rows, and pressure fluid means connected to said links for moving said bars between a position in which the bars are out of alinement and said spaced surfaces are in their retracted position and a position in which they approach alinement to effect vertical movement of the spaced surfaces of said support means to their raised positions whereby upon successive reciprocations of said chains and said support means the article is advanced through the furnace in a step by step manner.
